PETER BLOOMSBURG, JR., AND JAMES MOLYNEUX, OF BORDENTOWN, NEW JERSEY, ASSIGNORS TO THE BORDENTOWN MACHINE COMPANY.

Letters Patent No. 65,470, dated June 4, 1867.

IMPROVEMENT IN ROTARY VALVES FOR STEAM ENGINES.

The Schedule referred to in these Letters Patent and making part of the same.

TO ALL WHOM IT MAY CONCERN:

Be it known that we, JAMES MOLYNEUX and PETER BLOOMSBURG, Jr., of Bordentown, Burlington county, New Jersey, have invented an improved Rotary Valve for Steam Engines; and we do hereby declare the following to be a full, clear, and exact description of the same, reference being had to the accompanying drawing and to the letters of reference marked thereon.

Our rotary valve consisting of two revolving disks and an intermediate stationary disk, the several disks having openings arranged in respect to each other and to the ports of a cylinder, in the manner described hereafter. Our invention further consists of a device described hereafter, whereby the relative position of the two revolving disks and the cutting off of the steam may be regulated at pleasure.

In order to enable others skilled in the art to make and use our invention, we will now proceed to describe its construction and operation, reference being had to the accompanying drawing, in which—

Figure 1 represents a vertical section of our improved rotary valve.

Figure 2, a sectional plan on the line 1-2, fig. 1.

Figures 3 and 4, plan views.

Figures 5 and 6, elevations; and

Figure 7, a modification of the invention.

Similar letters refer to similar parts throughout the several views.

A represents a portion of the cylinder of a steam engine, *a* and *a'* being the two steam ports, and *b* the exhaust port. On the cylinder is formed the steam-chest *B*, which in this instance is shown without a cover or inlet pipe for the admission of steam. *D*, *E*, and *F* are three disks, adapted to the circular interior of the steam-chest. The lowest disk *F* is secured to a vertical spindle, *G*, and bears on the valve-face *e* of the cylinder, the under side of the disk having a recess, *f*, which serves as a continuation of the passage for the steam from the cylinder to the exhaust opening, as illustrated in fig. 1. Through this lower disk *F* is an opening, *h*, of the form illustrated in figs. 3 and 4. The intermediate disk *E* has projections *i*, *i*, adapted to recesses in the valve-chest, as seen in fig. 3, so that it cannot turn, and has two segmental openings, *j* and *j'*, of the form seen in figs. 3 and 4. The upper disk *D* is secured to a tubular spindle, *H*, fitting snugly, but so as to turn freely on the spindle *G*; and on the tubular spindle slides a collar, *I*, the vertical position of which may be controlled by a hand-lever, or it may be under the control of the governor of the engine. A pin, *m*, passes through this collar, through a spiral groove, *n*, in the tubular spindle, and through a vertical groove, *q*, in the inner spindle *G*. The upper disk *D* has a segmental opening, *t*, similar to those referred to above. On imparting a rotary motion to the spindle *G* the two disks *D* and *F* will revolve simultaneously. As seen in fig. 1, steam is in the act of passing into the cylinder through the opening *t* of the disk *D*, opening *j* of the disk *E*, and opening *h* of the disk *F*, and through the port *a*, while exhaust steam is passing from the cylinder at the opposite side of the piston, through the port *a'*, passage *f*, and exhaust port *b*. If the spindle *G* be turned to the extent of half a complete revolution, the disks *D* and *F* will be in such a position that steam will be admitted through the openings *t* and *h* of the revolving disks, and the opening *j'* of the intermediate disk to the port *a'*, while it is exhausting through the port *a*. The recess *f* is of such dimensions that it serves as an exhausting passage during one movement of the piston, the spindle *G* making a complete revolution for every revolution of the crank-shaft. As long as the opening *t* of the disk *D* is directly above the opening *h*, steam is admitted during the entire length of one movement of the piston, but on depressing the collar *I*, its pin, guided by the vertical slot *q* in the spindle *G*, will so act on the spiral groove of the tubular spindle *H* as to turn the latter to an extent commensurate with that of the collar's depression, the upper disk *D* being consequently turned so that its opening *t* will be in advance of the opening *h*; hence the disk *D* will cover the openings in the intermediate disk *E*, the supply of steam will be cut off from the cylinder before the piston arrives at the limit of each of its movements, and the point in the movement of the piston, where the steam is thus cut off, will depend upon the position of the collar *I*, which can be adjusted to any point desired. In the modification illustrated in fig. 7, the collar *I* is embraced and controlled by a nut, *M*, which has internal screw-threads adapted to external threads on the tubular spindle *H*. It will be evident that the collar *I*, and consequently the relative positions of the disks *D* and *F* may, by a suitable system of rods and levers, be placed under the control of the governor.

We claim as our invention, and desire to secure by Letters Patent—

1. A rotary valve, composed of the disk F, with its passage f, and opening h, and the disk D with its opening t, in combination with the within-described ports in the valve-face of the cylinder, and the intermediate disk E, with its openings j and j', the whole being constructed and operating substantially as and for the purpose herein set forth.

2. The disk F, and spindle G, with its vertical slot g, in combination with the disk D, the tubular spindle H, and its spiral slot, and the adjustable collar I, the whole being arranged for altering the relative positions of the said disks, substantially as set forth.

In testimony whereof we have signed our names to this specification in the presence of two subscribing witnesses.

PETER BLOOMSBURG, JR.,
JAS. MOLYNEUX.
